UNITED STATES PATENT OFFICE.

LOUIS WITTBOLD, OF CHICAGO, ILLINOIS.

OIL BURNER.

Application filed January 19, 1925. Serial No. 3,223.

This invention relates to an oil burner.

One object of the invention is to provide a simple, reliable and efficient oil burner having its parts so constructed and arranged as 5 to obtain the best results.

Another object is to provide an oil burner arrangement in which a screen is arranged to receive a relatively thin film of oil and from which the oil is removed and atomized 10 preparatory to being burned.

These and other objects are accomplished by the oil burner shown on the accompanying sheet of drawings, in which

Figure 1 is a longitudinal sectional view 15 of said burner, and

Figure 2 is a sectional view taken in the plane of line 2—2 of Figure 1.

Referring to the figures of the drawings, it will be noted that my oil burner includes 20 a main relatively large member 10, cylindrical in shape and forming a chamber 11, in which oil and steam or air may be fed and mixed for forming an atomized combustible mixture. Preferably oil is fed to the chamber 25 11 through a pipe 12 tapped into the side of the chamber member 10, the flow of oil through the pipe 12 being under proper pressure and controlled by a valve 13. Mounted within the chamber 11 and occupying 30 substantially the entire space therein and extending longitudinally thereof is a screen 14 rolled into the form of a tube having large surface area. Oil fed into the chamber 11 passes onto the screen forming a relatively thin film around the surface of 35 the screen for facilitating the taking up of the oil and atomizing same by a properly fed fluid such as steam or air. In this particular arrangement I prefer to use steam 40 and feed same to the chamber 11 through a

pipe 15 which is tapped into one end of the chamber member 10 so that the steam is directed longitudinally within and through the screen tube 14. The steam removes particles of oil from the screen and mixes with 45 and atomizes same during a progressive movement thereof. The mixed oil and steam leave the chamber 11 through a nozzle pipe or tube 16 tapped into the opposite end of said chamber member 10. The nozzle 17 50 at the end of member 16 is provided preferably with a relatively long narrow slit 18 through which the atomized oil mixture is ejected.

By means of this arrangement oil is 55 properly fed, mixed with a fluid such as steam or air and atomized preparatory to being forced through the nozzle and efficiently burned.

I claim:

An oil burner comprising a tubular member forming a chamber closed except for an oil inlet, a fluid inlet and a mixture outlet, an oil supply pipe connected to the side of said member for feeding oil to said chamber, a screen rolled into the form of a tube located in, supported by and extending lengthwise between the ends of said chamber and onto which screen oil is fed, a fluid supply pipe connected to one end of said chamber member and in alignment with said screen for directing a fluid through said tube of screen for removing oil therefrom and atomizing it, and a nozzle member connected to the other end of said chamber member through which atomized oil is ejected.

Signed at Chicago, Illinois, this 10th day of January, 1925.

LOUIS WITTBOLD.
